UNITED STATES PATENT OFFICE

123,087

DESIGN FOR A STEMMED ASH TRAY

Roderic M. Koch, Evansville, Ind.

Application May 10, 1940, Serial No. 92,290

Term of patent 7 years

To all whom it may concern:

Be it known that I, Roderic M. Koch, a citizen of the United States, residing at Evansville, in the county of Vanderburg and State of Indiana, have invented a new, original, and ornamental Design for a Stemmed Ash Tray, of which the following is a specification, reference being had to the accompanying drawing, forming a part thereof.

stemmed ash tray or the like, showing my design. Figure 2 is a top plan view thereof, on an enlarged scale; and

I claim:

The ornamental design for a stemmed ash tray, as shown.

RODERIC M. KOCH.
